J. H. STEWART.
SELF CLOSING PENDULUM HANGER FOR DOORS.
APPLICATION FILED JUNE 27, 1917.

1,275,174.

Patented Aug. 6, 1918.

WITNESS:

INVENTOR,
John H. Stewart,

Harry W. Bowen.

ATTORNEY.

UNITED STATES PATENT OFFICE.

JOHN H. STEWART, OF JAMAICA, NEW YORK, ASSIGNOR TO THE COBURN TROLLEY TRACK M'FG CO., OF HOLYOKE, MASSACHUSETTS, A CORPORATION OF MASSACHUSETTS.

SELF-CLOSING PENDULUM-HANGER FOR DOORS.

1,275,174.

Specification of Letters Patent.

Patented Aug. 6, 1918.

Application filed June 27, 1917. Serial No. 177,300.

To all whom it may concern:

Be it known that I, JOHN H. STEWART, subject of the King of Great Britain, residing at Jamaica, in the borough of Queens 5 and the State of New York, have invented certain new and useful Improvements in Self-Closing Pendulum-Hangers for Doors, of which the following is a specification.

This invention relates to improvements in 10 doors, particularly in doors for closing elevator wells, or, wherever a quick acting and quietly operating sliding door can be conveniently used. The present invention relates to the type of door which is supported 15 by means of swinging bars or pendulums.

An object of the invention is to provide a 20 door construction which is of simple design and very easy in operation. It is practically noiseless, and one that does away with the ordinary supporting anti-friction rollers 25 at the top and bottom edges. It is of the type shown, described, and claimed in Letters Patent granted to me on Dec. 12, 1916, No. 1,208,690. In the present construction 30 the weighted end of the pendulum is located within a compartment or inclosing casing which is formed within the panel-work of the door, the upper end of the pendulum being connected to a fixed support. A further 35 object of the invention is to provide means for attaching the sliding door to another door, preferably a swinging one, that can be opened if desired to increase the width of the doorway, although usually only one of 40 the doors is used at a time. The two doors are then moved as a unit. These and other objects of the invention will appear in the body of the claims.

Referring to the drawings:

Figure 1 is a side elevational view showing the sliding and swinging doors in closed position, the weighted end of the pendulum of the sliding door being shown in dotted lines and located within an inclosing casing 45 which is set into the panel work of the door, the right end portion of this figure representing the door that is pivotally connected to the door casing and with means for locking the same against a swinging movement; 50 Fig. 2 is a horizontal sectional view on the line 2—2 of Fig. 1, the full lines showing the doors in closed position and the dotted lines showing the two doors swinging outward as a unit;

Fig. 3 is a horizontal sectional view on the line 3—3 of Fig. 1 showing the interior construction of the casing in which the weight that operates the door is located; 55 Fig. 4 is a detailed view of the upper end of the pendulum or bar which is attached to the normally closed door. This figure shows the position that the doors assume when the pendulum supported door is moved into a position at the side of and adjacent to the normally closed door; 60 Fig. 5 is a sectional elevational view on the line 5—5 of Fig. 1 showing the manner of connecting the pendulum to the weight also showing the manner in which the inclosing casing for the weight is set into the 65 panel work of the door.

Referring to the drawings in detail: The usual frame work or casing of the doorway is indicated at 1, 2, and 3. The two doors employed for closing the doorway are indicated at 4 and 5. The door 4 is a sliding one, by means of a pendulum construction for supporting the same while the door 5 is designed to be a swinging one, the same being connected to the casing 2 by means of 70 the hinges 6.

Referring first to the construction of the door 4: 7 indicates a link or bar, the upper end of which is pivotally connected to the fixed channel and guide iron 8 that is secured to the door 5 (see Fig. 4) by means of the pivot 9. Its lower portion is pivotally connected to the arm 10 of the weight 11, which weight is pivotally hung within the inclosing casing 12, the pivot being indicated at 13, which in turn is supported by means of the brackets 14 and 15. The bracket 14 is secured to the panel 16 which is located at the rear portion of the casing, while the bracket 15 is attached to and depends from the bracket 14. The weight 11 is formed with a recess 17 for the purpose of receiving additional weights for the proper 80 balancing and operation of the door 4. Located between the ends of the link 7 is a 85 sliding and pivotal support 17' which passes through an elongated slot 18 in the bar 7. This pendulum or supporting bar is guided by means of the swinging housing 19. This 90 construction permits the pendulum 7 not only to have a swinging movement about the pintle 17' but a sliding movement through the casing 19 as well. Also attached to the 95

100

105

link 7 is link 20 at substantially its middle point, the upper end of which is pivotally connected to the door 4 by means of the pin 21. It will be noticed from Fig. 4 that the 5 upper end of the link 20 is bent inward so that the pintle 21 is located in the recessed or cut-out part of the upper end of the door 4. The purpose of this is to permit the links 7 and 20 to pass by each other in the opening 10 and closing operations. The pivotal connection between the links 7 and 20 is indicated at 22. The lower end of the link 20 is connected to the link or bar 23 by means of the pivot 24. The right hand end of the link 15 23 is pivotally connected to the swinging door 5 at its outer edge, as shown and indicated at 25. The swinging door 5 is normally locked against movement by means of the sliding bolts 26 which are located at the 20 top and bottom portions of the door 5 and near the inner edge of the same. Door 4 is locked to the casing 1 by means of the swinging latch 27 which latch is pivotally connected to the swinging housing 19, as indicated at 28. The inner end of this latch 25 is formed with a curved upwardly extending portion 29 which the operator grasps to unlatch or unlock the door 4 and also for sliding this door into its open position as indicated by the dotted lines of the links or bars 30 7 and 20. The rotation of housing 19 causes the latch 27 to move inwardly on door 4 in opening so that it does not obstruct the opening when door 4 is opened as shown in dotted 35 lines.

One of the important features of the present invention is the doing away with supporting and guiding rollers which in this 40 class of inventions are usually employed at the top and bottom edges of the movable door for supporting the door and for reducing friction. The present construction is wholly a pendulum device for supporting and permitting the sliding of the door 4; 45 the upper end of which is guided by means of the channel iron 8.

Referring now to the construction shown in Fig. 2 it will be seen that both doors 4 and 5 are in the closed position as indicated 50 by the full lines. The dotted lines indicate that the door 4 has been moved toward the right by the operator, lifting the latch 27 and moving the door into parallel relation with and adjacent to the door 5, as shown. 55 If the two doors are to be opened the bolts 26 of the door 5 are then withdrawn from their sockets from the sill or floor portion when the two doors can then be readily 60 swung outward, as shown in the dotted lines in Fig. 2, thus permitting the full width of the doorway to be utilized although normally the door 5 is bolted and only the door 4 is ordinarily used.

It should be mentioned and understood 65 that suitable adjusting or take-up devices

are employed for positioning the links 20 and 23, whereby the door 4 can be slightly tipped about the pivot 22 in order to bring the same into an accurately vertical position. This adjusting device may be applied either 70 to the link, 23 or the link 20, as desired. After the operator releases the latch 27 and pulls toward the right on the same the door 4 will be moved to its open position. This operation causes the weight 11 to assume the 75 elevated position shown at the right of Fig. 1 but not to hold the door 4 open. As the operator releases the latch 27 the weight 11 will automatically return the door 4 to its 80 normal or closed position again. The construction therefore embodies a self-closing door construction of the pendulum type and one that is very easy to operate and at the same time practically noiseless in its 85 operation. It also provides a door that cannot be left open through carelessness of the operator but will close and latch automatically upon releasing the handle insuring safety when used for closing elevator well 90 openings.

An important feature of the present invention is the fact that in the construction shown in the drawings whereby the usual rollers are omitted and the doors are supported entirely by the pendulums and thus 95 producing a construction that is noiseless in operation, the pendulum bars which are substituted to act in the place of rollers or guides performing the usual function of the rollers or guides. Another important feature 100 in connection with the present invention is the entire elimination of the usual transom construction which is required to carry the track in ordinary sliding and swinging construction, whereby the noiseless feature 105 is produced. Such a construction is desirable 110 in hospitals and hotels where elevators are used for freight as well as for passenger service. It is also to be understood that the present construction is not confined to any particular use as the same may be used for barn doors, house and freight car doors, as well as passenger and Pullman car doors and street railway coaches, if desired.

What I claim is:

1. The combination with a doorway, of a pendulum supported door therefor, comprising a bar having a pivotal connection with a fixed support, a weight connected to one end of the bar and to the door, the bar being 115 also connected to the door, a second bar connected to the door and to the first mentioned bar, and means for pivotally connecting the second bar to a fixed support, the pivotal connection of the first bar with the 120 door permitting the door to travel in a straight line during its opening and closing movements.

2. In combination, a sliding door, means 125 for pivotally supporting the door compris- 130

ing a swinging bar connected to the door and to a fixed support, respectively, a weight connected to the free end of the bar for returning the door to its closed position, and 5 means connected to the bar, door, and fixed support, for controlling the movements of the bar and door.

3. In a sliding door the combination, bars for pivotally supporting the door, means 10 connected to one of the bars and to a fixed support for controlling the movements of the bars and door, a weight connected to one of the bars and to the door for returning the door to its closed position.

15. 4. In a sliding door the combination, a bar pivotally and slidably connected to the door, one end of the bar having a weight pivotally connected thereto and to the door for normally retaining the door in its closed 20 position, the other end of the bar being connected to a fixed support, a second bar connected to the door at one end, and to said bar, a link connected to the other or free end of the second bar and to a fixed support.

25. 5. In a door construction the combination, of a bar having a sliding and pivotal connection with the door, one end of the bar being connected to a support, a weight connected to its free end, and pivotally connected to the door, at a point substantially 30 in a line passing through its center of gravity, the weight being confined in an inclosing casing of the door, and means connected to a support and the bar for causing the door 35 to always retain its vertical position during its movements.

6. A door comprising two sections, one of the sections designed for sliding movements, means for pivotally connecting the two sections of the door as a whole to a support to 40 permit of a swinging movement of the two sections and including a bar having a sliding and pivotal connection with one of the door sections and attached to the other door section at one end, its other end having a 45 weight connected thereto and to the sliding door section, a second bar connected to the said bar at a point substantially midway of the length of the second bar, one end being 50 connected to the sliding door section and the other end to the other door section, whereby when the sliding door section is moved it 55 will travel in a straight line and automatically return to its closed position independent of the movement of the other door section if the operator releases the same at a point in its travel or its full open position.

7. A self-closing door, comprising in combination, a pendulum or swinging bar pivotally attached to the door and a fixed support for supporting the door, a counterbalancing weight attached to the bar for returning the door to its initial position after being moved therefrom, means connected to 5 the door and pendulum to maintain the axis

of the door in an upright or vertical position when considered with relation to its initial position.

8. A self-closing sliding door, comprising in combination, a pendulum or swinging bar pivotally attached to the door in a sliding and swinging manner and also pivotally connected to a fixed support construction, said bar occupying a normally inclined position when the door is in either an open 70 or closed position, a weight attached to the bar, means attached to pendulum and door for controlling the position of the door during its movements, and a latch connected to the pendulum, whereby when the door is 75 operated the latch will be simultaneously moved in unison with the pendulum into and out of its latching position.

9. A self-closing door, comprising in combination, a swinging bar connected to the 85 door, and to a fixed support, respectively, a counterbalancing weight for moving the door and attached to the bar and door for automatically returning the door to its initial position, two links 20 and 23, one being 90 connected to the swinging bar and door and the other to said link and support for controlling the position of the door during its movements.

10. In a self-closing door construction the 95 combination, of two door sections, a bar pivotally connected to one door and to a second door for supporting the first door, a weight attached to the first door and bar for returning the first door in its initial position, the second door being pivotally connected to the casing or door frame, two links connected together, one end of one link being connected to the first door and its supporting bar and the other end of the other link 100 being connected to the second door for controlling the movements of the first door, whereby when the first door is moved to its open position adjacent the second door the two doors, as a unit, may be swung on the 110 pivotal connecting means which supports the second door.

11. A self-closing door, comprising, in combination, a bar pivotally and slidably connected to the door at a point in a line 115 passing through its center of gravity, a weight connected to the lower end of the bar, said bar being in a normal inclined position and connected to a fixed support at its upper end, means comprising links for 120 maintaining the door during its movement in a vertical position, and a latch connected to the bar and movable therewith for placing the same in its latching and unlatching position.

12. The combination with a door opening, of two door sections, one section adapted for sliding movements into a position parallel with the other section, said other section having a pivotal connection with the 130

door casing for swinging movements, a supporting bar attached to the sliding section and to the swinging section, a weight attached to the bar and sliding section, links connected to the sliding section, bar and swinging section for maintaining the sliding section in a vertical position as the sliding section is moved, the movements of the sliding section permitting the two sections to be moved as a unit.

13. In a sliding door construction, the combination, of means for supporting the door to permit sliding movements to its open position and to automatically return to its closed position, said means including a pendulum bar pivotally connected to a fixed support near its upper end and a sliding and pivotal connection with the door near its lower end, a weight connected to the door

and to the lower end of the pendulum bar, 20 as described and means for maintaining the door in a vertical position during its movements.

14. In a sliding door construction, means for supporting the same to permit the door to be opened and to automatically return to its initial or closed position including a pendulum bar having a pivotal connection with a fixed support for operating the door and a sliding and pivotal connection with the door 30 to permit lateral movement of the door, and a weight pivotally connected to the pendulum bar and to the door for returning the door to its closed position after the same has been opened and means for maintaining the door in a vertical position during its movements.

JOHN H. STEWART.
